FRANK J. VRBAS, OF RAWLINS COUNTY, KANSAS.

CANE-SEED CUTTER.

1,176,004.

Specification of Letters Patent. Patented Mar. 21, 1916.

Application filed February 27, 1915. Serial No. 11,081.

To all whom it may concern:

Be it known that I, FRANK J. VRBAS, a citizen of the United States, residing in the county of Rawlins and State of Kansas, 5 have invented a new and useful Cane-Seed Cutter, of which the following is a specification.

This invention has reference to cane seed cutters and its object is to provide a device 10 whereby cane may be readily and expeditiously cut by hand without necessitating the expenditure of an undue amount of force.

In accordance with the present invention 15 there is provided a simple frame-like stand with a rock member mounted thereon and carrying at one end a rotary cutter, while the other end of the rock member is arranged at an angle to that end carrying 20 the cutter and provided with a manipulating handle. The frame is formed with a bed member longitudinally slotted for the passage of the cutting edge of the cutter and is curved appropriately about the axis of 25 rocking of the cutter carrier, while near one end the bed is provided with a laterally offstanding support for the cane to hold it while being cut, the bed being shaped to coact with the cane-carrying support to prevent displacement of the cane while being 30 subjected to the action of the cutter.

The invention will be best understood from a consideration of the following detailed description, taken in connection with 35 the accompanying drawings forming a part of this specification, with the further understanding that while the drawings show a practical form of the invention, the latter is not confined to any strict conformity with 40 the showing of the drawings, but may be changed and modified so long as such changes and modifications mark no material departure from the salient features of the invention.

45 In the drawings:—Figure 1 is a side elevation of the improved cane seed cutter. Fig. 2 is a plan view thereof with some parts shown in section. Fig. 3 is a longitudinal vertical section taken about midway 50 of the width of the frame and showing some parts in elevation. Fig. 4 is a section on the line 4—4 of Fig. 1, but shown on a larger scale.

55 Referring to the drawings there is shown a curved bed 1 consisting of two elongated

plates 2, 3, respectively, spaced apart laterally of their length to provide an elongated narrow slot or opening 4 between them. At one end these two plates are secured together in proper spaced relation by a cross 60 piece 5 and near the other end by another cross piece 6, which, however, is formed intermediately of its length with an offset bend 7 at the slot 4 for a purpose which will hereinafter appear. The bed 1 is supported upon legs 8, 9, suitably connected together and to the bed by longitudinal braces 10.

The parts so far described may be made of band or sheet steel properly bent and 70 riveted or otherwise secured thereto.

Erected on the top of the bed near one end are standards 11 provided with braces 12 so that these standards are suitably stiffened by the braces. The standards in the 75 particular showing of the drawings rise from one end of the bed and are inclined toward the other end of the bed, which latter end has a return bend 13 partly overhanging the bed.

80 The upper ends of the standards 11 are connected together by a bolt 14. Mounted to rock on the bolt 14 about midway of its length is a hub 15 with a bifurcated arm 16 projecting from one side and ears 17 from the other side, but the ears and arm are in obtuse angular relation one to the other. The hub 15 is connected on opposite sides by 85 springs 18 to respective standards 11, so that the hub and its arms which constitute a 90 rockable carrier are constrained toward a position remote from the overhang 13. The arm 16 is traversed near its outer end by a bolt 19 on which is mounted a rotary or 95 disk cutter 20. The ears 17 carry a handle 21. The disk 20 is of a diameter to have its peripheral cutting edge projecting through the slot 4 and the curvature of the bed is such that the cutting edge of the disk always 100 projects into or through the slot.

At that end of the bed adjacent to the overhang 13 and projecting from one side thereof is a support 22 designed to sustain the bound cane to be cut. This support may be made of steel rod, as shown, and is of approximately U-shape and curved into conformity with the curvature of the bed, or it may be otherwise constructed. The ends of the legs of the U-shape support 22 are 105 riveted or otherwise secured to the member 110

2 of the bed, so that the whole support is more or less inclined in the direction of the length of the bed. One leg is bent to rise higher than the bed at the point where it is located, this rising side of the frame or support being indicated at 23, and is designed to provide an abutment for the cane, preventing it from moving too close to the mid portion of the bed.

10 Ordinarily the cutter 20 is constrained by the springs 18 to maintain a position out of the way of a bundle of cane lodged on the support 22 in transverse relation to the bed 1. When force is applied to the 15 handle 21 tending to depress it, the hub 15 is rocked on the bolt 14 in a direction to carry the cutter toward the cane support and the overhang portion 13 of the bed. The cutter being free to rotate readily severs the bundle of cane where it engages it and any tendency of the cane to move ahead of the cutter is prevented by the overhang 13 which effectively resists any movement of the cane, so that the cutter is readily 20 forced through the cane to sever it. The lower upstanding portion 23 of the cane support prevents the cane from falling under the action of gravity too close to the cutter.

25 30 The whole device is of extremely simple construction and very readily and cheaply built, while the angularity of position of the handle permits the operator to apply his weight to the handle in a manner to force 35 the cutter through the cane by a direct application of force in a manner best adapted to the operator so that great exertion is not needed.

What is claimed is:—

40 1. A cane seed cutter provided with an elongated curved bed having near one end a support for the cane and also formed with a slot extending lengthwise of the bed and through the cane support, and a rotary cutter 45 provided with a rockable support mounted above the bed with the cutter projecting through the slot, the axis of the rockable support being substantially concentric with the curvature of the bed.

50 2. A cane seed cutter provided with an elongated curved bed with a support for the cane at one end of the bed and with a longitudinal slot extending through the bed and including a cane support, and a rotary cutter 55 provided with a rockable mounting having its axis of rocking movements located above and substantially concentric with the curvature of the bed, and said bed rising in the direction of travel of the cutter about its axis of rocking through that portion of the bed constituting the support for the cane and terminating in a return overhang forming an abutment for the cane.

60 65 3. A cane seed cutter comprising a bed and support therefor, with a standard

erected at one end of the bed, and a rotary cutter and support therefor with the support mounted on the standard for rocking movements, the bed being provided with a longitudinal slot for the reception of the cutting edge of the cutter and curved on substantially an arc struck from the axis of rocking of the cutter, said bed having the end toward which the cutter rocks rising and provided with a return curve, and a support for cane carried by the said end of the bed having the return bend and projecting laterally therefrom and also curved in the direction of the length of the bed with one side low and the other side high. 75

4. A cane seed cutter comprising a bed and support therefor with a standard erected at one end of the bed, and a rotary cutter and support therefor with the support mounted on the standard for rocking movements, the bed being provided with a longitudinal slot for the reception of the cutting edge of the cutter and curved on substantially an arc struck from the axis of rocking of the cutter, said bed having 80 the end toward which the cutter rocks rising and provided with a return curve, and a support for cane carried by the said end of the bed and projecting laterally therefrom and also curved in the direction of 85 the length of the bed, said support for the cane having the side remote from the return end of the bed upstanding to provide a holding abutment for the cane. 90

5. A cane seed cutter comprising a bed and support therefor, with a standard erected at one end of the bed, and a rotary cutter and support therefor with the support mounted on the standard for rocking movements, the bed being provided with a longitudinal slot for the reception of the cutting edge of the cutter and curved on substantially an arc struck from the axis of rocking of the cutter, and said bed having the end toward which the cutter rocks rising and provided with a return curve, and a support for cane carried by the rising end of the bed and stopping short of the central portion of the bed, said cane support projecting laterally from the bed and also curved in the direction of the length of the bed, said support for the cane having the side remote from the return end of the bed upstanding to provide a holding abutment for the cane, and the cutter support being provided with spring means for constraining the cutter away from the end of the bed having the cane support. 100

6. A cane seed cutter having a bed with a longitudinal slot therein, said bed having at one end a rising curve terminating in a return bend and at said end provided with a cane support projecting laterally therefrom and correspondingly curved with its lower side uprising to form an abutment 115

support for cane, and a rockable rotary cutter mounted on the bed beyond that side of the cane support remote from the return bend of the bed with its cutting edge projecting through the slot and movable lengthwise of the bed across the cane support to the uprising curved portion of the bed.

In testimony, that I claim the foregoing as my own, I have hereto affixed my signature in the presence of two witnesses.
